DESIGN FOR A JEWELRY FINDING FOR CLIPS OR OTHER SIMILAR ARTICLES OF JEWELRY

Albert Freedman, Brooklyn, N. Y.

Application March 3, 1941, Serial No. 99,317

Term of patent 14 years

To all whom it may concern:

Be it known that I, Albert Freedman, a citizen of the United States of America, residing in Brooklyn, county of Kings and State of New York, have invented a new, original, and ornamental Design for a Jewelry Finding for Clips or Other Similar Articles of Jewelry, of which the following is a specification, reference being had to the accompanying drawing, forming part thereof.

Fig. 1 is a plan view of a jewelry finding for clips or other similar articles of jewelry showing my new design.

Fig. 2 is an edge view thereof.

I claim:

The ornamental design for a jewelry finding for clips or other similar articles of jewelry, as shown.

ALBERT FREEDMAN.
